George W. McGill

UNITED STATES PATENT OFFICE.

GEORGE W. MCGILL, OF RIVERDALE, NEW YORK.

SUSPENDING DEVICE.

SPECIFICATION forming part of Letters Patent No. 337,970, dated March 16, 1886.

Application filed January 23, 1886. Serial No. 189,465. (No model.)

To all whom it may concern:

Be it known that I, GEORGE W. MCGILL, a citizen of the United States, residing at Riverdale, in the city and county of New York, 5 State of New York, have invented a new and useful Improvement in Suspending Devices, of which the following is a specification, reference being had to the accompanying drawings, making part of the same, and to the figures of reference marked thereon, in which the same numerals of reference indicate corresponding parts.

The object of my invention is to produce a cheap and strong device for suspending or 15 hanging cards, calendars, pictures, or other prints, &c., upon nails, hooks, rods, &c.; and it consists in a metal loop or hook attached by a hinge-connection with an adhesive attaching-tablet of paper, cotton cloth, linen, 20 or linen-backed paper, or other suitable material, the latter adapted to be attached to a card or other print to be suspended by means of a coating of mucilage or other adhesive material, and in manner to admit of the metal 25 loop or hook being turned or closed down on or over the card or print, to allow the same to be neatly and safely packed for transportation, or to be mailed.

My improvement consists in a novel and 30 peculiar form given the adhesive attaching-tablet to enable it to be readily connected with its metal loop or hook and to lock them together.

In the drawings, Figure 1 represents the 35 adhesive attaching-tablet. Figs. 2 and 3 represent forms of metal loops of the device. Fig. 4 is a view in perspective of the adhesive attaching-tablet and metal loop connected together as intended and ready to be applied. 40 Fig. 5 is a front view of the device, showing its loop turned or closed down. Fig. 6 represents the device applied to a card, b, or other print. Fig. 7 is a vertical sectional view of the device so applied, taken on line *xx* of Fig. 45 6; and Fig. 8 is a view similar to Fig. 6, excepting that the upper part of the metal loop is fashioned in hook form instead of ring form.

The paper or other material from which the attaching-tablet is cut has one of its surfaces 50 treated with a coating of suitable adhesive material—such as mucilage, glue, gum, &c.—which is dried thereon, and which, by moisten-

ing or heating, will become adhesive or sticky, and admit of the tablet being attached to other papers and such like articles by pressing it 55 thereon. This tablet or attaching part of the device is cut in T form—that is, having a top part, 1, and a body part, 2.

The metal loop or hook is made from a single piece of suitable wire terminating in a bottom oblong eye, 5, each end of the wire forming part of such eye.

The body part 2 of the attaching-tablet may be of any length desired, but in width it is somewhat less than the width or length of the 65 inside of the eye 5 of the metal loop, and is provided with ears or barbs 4 4—one on each side near its connection with the top part 1, toward which the broad part of these barbs 70 face. The body part 2 is preferably pointed at its free end, and the tablet and loop are connected together by running the body part 1 of the tablet through the eye 5 of the loop, which latter is forced over the barbs 4 4 onto the intermediate neck, 3, where it is held by 75 the barbs 4 4, as shown in the drawings.

In running the barbed body part 2 of the attaching-tablet through the eye of the metal loop, the barbs 4 4 spring the eye open in their 80 passage through it, and the resilience of the wire closes the eye after such passage. The metal loop and its adhesive tablet are by this construction and arrangement held together in position for ready use.

The device is applied by moistening or heating 85 the adhesive surface of the tablet and pasting its top part, 1, on a card or other article to be suspended just below its top margin and folding the body part 2 over the top of such card and pasting it to the opposite side of the 90 same in manner to bring the intermediate neck, 3, of the tablet and the wire loop above the card, as shown in the drawings. The loop is thus held above the card by a hinge-connection with the tablet, which admits of its being 95 turned or closed down on the same, when desired, for transportation, &c., of the card, as shown in Fig. 5.

The adhesive material may be applied to the tablet after the latter is cut from its stock; 100 but the better plan is to first prepare the stock with a coating of it, as hereinbefore described.

What I claim as my invention, and desire to secure by Letters Patent, is—

In a suspending device consisting of the wire loop and T-shaped adhesive tablet herein described, the body part 2 of the tablet, provided with barbs 4 4, adapted to spring open 5 the eye of the wire loop and to hold the loop on the tablet-neck 3, substantially as and for the purposes herein set forth.

In testimony that I claim the foregoing I hereunto affix my signature in the presence of two witnesses.

GEORGE W. MCGILL.
